DESIGN FOR A BENCH

Clytie Ann Thomson, Roanoke, Va.

Application February 10, 1947, Serial No. 136,811

Term of patent 7 years

(Cl. D33—7)

To all whom it may concern:

Be it known that I, Clytie Ann Thomson, a citizen of the United States, residing at Roanoke, Virginia, in the county of Roanoke and State of Virginia, have invented a new, original, and ornamental Design for Bench, of which the following is a specification, reference being had to the accompanying drawing, forming part thereof.

Fig. 1 is a front perspective view of a bench showing my new design; and

Fig. 2 is a rear elevational view thereof.

I claim:

The ornamental design for a bench, as shown.
CLYTIE ANN THOMSON.
